UNITED STATES PATENT OFFICE.

LOUIS CARP, BEREL BECKER, AND FRANK BECKER, OF NEW YORK, N. Y.

BUTTON.

Application filed March 1, 1927. Serial No. 171,787.

The present invention relates to improvements in buttons and has for its principal object to provide a button which is of such construction as to permit the same to be secured to a garment or other suitable article, either by hand or a button sewing machine in a practical and economical manner.

One of the important objects of the present invention resides in the provision of a button which comprises a base section, and a separable head, the head being adapted to be secured on the base section to provide a unitary structure.

Another important object of the present invention relates to a method of attaching buttons on a garment, either by hand or machine, which consists in initially securing the base of the button to the article on which the button is to be secured, and subsequently securing the separable head on the base, whereby to provide a permanent and unitary button structure.

A further object of the present invention is to provide a button of the above-mentioned character wherein, the head of the button cannot be removed from the base section, thus producing a unitary button structure which will present a neat appearance when assembled.

A still further and important object is to provide a button of the above-mentioned character which is simple in construction, inexpensive, strong and durable and further well adapted for the purposes for which it is designed.

Other objects and advantages of the present invention will become apparent during the course of the following description.

In the accompanying drawing forming a part of this specification and in which like numerals designate like parts throughout the same,

Figure 1 is a side elevation of the button embodying our invention showing the same attached to a garment;

Figure 2 is a front elevation thereof;

Figure 3 is a vertical sectional view taken approximately on the line 3-3 of Figure 2, showing the manner in which the head is secured to the base;

Figure 4 is a front elevation of the base section showing the same attached to the garment;

Figure 5 is a vertical sectional view of a modification of the button;

Figure 6 is a similar view of a still further modification;

Figure 7 is a detail perspective view of the head of the button; and

Figure 8 is a perspective view of a modified form of the head.

In the drawing wherein for the purpose of illustration is shown a preferred embodiment of our invention, the numeral 1 designates generally our improved button, the same comprising the base section 2 and the separable head 3. The base section 2 is formed of flexible metallic material and is substantially circular in shape. This base section is furthermore substantially cup-shaped and the free edge thereof is rolled and disposed inwardly to provide a retaining flange 4 in the manner as clearly illustrated in Figure 3. The purpose of this retaining flange 4 will be hereinafter more fully described.

The central portion of the back of the base section 2 is stamped outwardly to provide the shank 5 and the rear end portion of this shank is substantially flat as clearly shown in Figures 1 and 3.

Formed at the juncture of the back portion of the base 2 with the shank 5 are a series of openings 6 for the purpose of permitting the securing thread 7 to extend therethrough whereby the button 1 may be attached to the garment A. In the present instance, four of such holes are shown although it is to be understood that we do not wish to limit ourselves to any particular number. As many holes may be provided as is desired or as deemed necessary for securing the base 2 properly on the article to which the button is to be secured.

The separable head 3 may be formed of any flexible or non-flexible material and may be constructed or stamped out from metal, celluloid, bone, horn and the like. This head 3 is preferably in the form of a cap as is clearly shown in Figure 7 of the drawing and the flange 8 of the cap head 3 is flared slightly outwardly. The outer face of the head is slightly bulged and the flange portion 8 is of such diameter as to snap into the open front face of the base 2 and fit against the rolled flange 4 of the base 2.

In attaching the button, the construction of which has been more fully described, the base section 2 is placed on or against the garment or other article to which the button is to be secured and the thread 7 is passed

through the holes 6 and the garment A either by the use of a hand needle or a button sewing machine so that the base will be properly attached to the garment in the 5 manner shown in Figure 4. The separable head 3 is then snapped into the base 2 and the rolled flange 4 will co-operate with the flared flange 8 of the head 3 in securing the latter permanently on the base thus 10 providing a unitary button structure which cannot be readily disassembled.

When the head of the button is properly supported on the base, the same will completely cover the thread so that the securing 15 thread will not be visible from the front side of the button thereby presenting a button having a neat appearance. Any suitable design or configuration may be arranged on the head as may be desired. Also the head 20 may be covered with cloth or other fabric.

In Figure 5 of the drawing, we have shown a modification of the button wherein the same consists of three parts whereas the button heretofore fully described only 25 consists of two parts; namely, a base section and a head. In this particular modification, the outer edge of the base 9 is not rolled and encircling this edge portion is the inner end portion of a band 10. This band fits snugly 30 around the edge portion of the base 9 and the outer edge portion of the band is rolled inwardly to provide a retaining flange 11 for co-operation with the flared flange of the head in the manner clearly illustrated in this 35 particular figure.

In Figure 6, a still further modification is shown wherein the button consists of two parts, namely, a head and a base section. However, the base section 12 is formed with 40 an annular groove or channel 13 at a point inwardly from the rolled outer edge 14 and the head 15 has its outer edge portion 16 curved inwardly to snap over the outer peripheral face of the rolled flange 14, and 45 the edge of this inwardly directed portion 16 extends into the annular channel or groove 13.

In Figure 8 of the drawing, there is shown a modification of the head wherein the 50 flanged portion is formed with a series of slits 17 which extends inwardly from the

outer edge of the flange to a point adjacent the bulged or central portion of the head and the purpose of this construction is to provide means whereby the flared flanged 55 portion of the head may be slightly flexed in order to insure a snug fit of the head of the button on the base section 2.

It will thus be seen from the foregoing description, that we have provided a button 60 structure which will save considerable time and labor in attaching buttons to garments or other articles and by assembling and attaching a button in the manner as herein shown and described, considerable expense 65 will be saved. Furthermore, the use of complicated machinery in sewing on buttons such as must now necessarily be used in connection with certain styles of buttons will be obviated. The simplicity in which the present button is constructed enables the same to be readily and easily assembled and attached and when the several parts of the button are 70 thus assembled, a permanent and unitary structure will be provided. 75

While we have shown the preferred embodiment of our invention, it is to be understood that various changes in size, shape and arrangement of parts may be resorted to without departing from the spirit of the 80 invention and the scope of the appended claim.

Having thus described our invention, what we claim is:

In a method of applying buttons on a support, wherein the button consists of two separate parts, a base, and a head, the base being formed with a central struck out shank and openings arranged at the juncture of the base with the shank to permit a threaded 85 needle to pass either vertically or horizontally through the openings and secure the base on the support; consisting in initially sewing the base on the support and subsequently securing the head on the base to conceal the thread and provide a permanent 90 unitary button structure. 95

In testimony whereof we affix our signatures.

LOUIS CARP.
FRANK BECKER.
BEREL BECKER.
